HAMMER

Norman C. Woodin, Rock Island, Ill.

Application March 28, 1941, Serial No. 385,702

6 Claims. (Cl. 125—33)

This invention relates to hammer mechanism of the mechanically driven type, as contrasted with pneumatic hammers, and will be described as applied to a portable gasoline engine driven hammer.

The general object of the invention is to provide more mobile, effective and cheaper equipment than the conventional cumbersome, expensive pneumatic equipment used by construction contractors, quarry men and the like for wrecking, drilling, tamping, spike driving and similar operations.

The particular object of the invention is to provide a light, strong and powerful hammer driven mechanically rather than pneumatically.

Another object is to provide a hammer that will strike a relatively heavy blow in slower rhythm than conventional pneumatic hammers.

And a still further object is to provide a hammer mechanism wherein the reaction or rebound forces are largely absorbed within the hammer itself.

Other objects and benefits will be disclosed in the following descriptions and drawings in which:

Fig. 1 is a front elevation view of my hammer with one section broken away to disclose the arrangement of interior parts; and

Fig. 2 is a side elevation view of my hammer with the upper section broken away, as indicated in the section lines 2—2 of Fig. 1, to better show the hammer mechanism.

Now referring to the figures, and at the outset particularly to Fig. 1, I designate the power source, in this instance a gasoline engine, by the numeral 5. It will be understood, of course, that any suitable source of power, such as an electric motor, may be substituted for the gasoline engine. The engine is supported on a base 6 integral with the main frame of the hammer 7. A double V-belt drive pulley 8 is mounted on the engine shaft and through dual V-belts 9 drives the drive pulley 10 journaled on the main shaft 11 which is suitably mounted in ball bearings 12 and 13. A cone clutch 14 co-acting with a female clutch 10' on the pulley 10 provides the driving connection. The clutch 14 has a yoke-bearing extension 14' which is mounted on a conventional over-ride clutch of the roller type 15, and this entire clutch mechanism, including the cone clutch 14, is urged inwardly into clutching contact with the pulley 10 by the compression spring 16. Control means for the clutch is provided by a conventional yoke lever 17 actuated by the link 18 and handle 19. It will be

appreciated that the operator while supporting the hammer by the handles 20 and 21, may stop hammer operation by gripping the handle 19 against the handle 20 and may start the hammer by releasing his grip. This is a conventional method for controlling hammer operation, and it is believed that with the above explanation the operation of the device will be well understood.

The use of the over-ride clutch 15 will be readily appreciated when the operation of the hammer mechanism is explained and its use is necessitated by the fact that provision must be made to permit the hammer to move faster than the normal driving speed of the pulley, and this requires the use of an over-ride clutch, as is well understood in mechanics.

Now referring to Fig. 2, the hammer mechanism is shown as it would appear on the section lines 2—2 of Fig. 1. The main drive shaft 11 is shown in section and affixed on it is the crank 22 carrying a flange roller 23 slidable in the slot 24 of the pivotal arm 25. This arm, which is a hammer drive arm, is pivoted on a roller 26 slidable in a pivot bracket 27 affixed to the side 25 of the case as shown. On the outer end of the drive arm 25 a roller 28 is journaled, and this roller moves vertically in a guideway 29 also affixed in the hammer case 7. Dual links 30 are also pivotally attached to the arm 25, as better shown in Fig. 1. In the opposite end of the links 30 a connector link 32 is pivoted. This connector link in turn is pivotally attached to the hammer 33. A roller 31 is mounted on the same pivot pin connecting the links 30 and 32. It will be noted that the link 32 has an extension 32' extending upward beyond the pivot point and that between the links 30 is fixed a filler plate 30'. It will readily be appreciated that the extension 32' will strike the filler plate 30' at a point which will prevent the links 30 and 32 from pivoting inward beyond the dead center point and, therefore, all pivotal action of the links 30 and 32 must be outward. This action is aided by the leaf spring 34 bolted on the filler plate 30' and held by lock nuts 35. Limitation of this movement is provided by the angle guide 32'.

By referring to the dotted outline of the mechanism as shown in Fig. 2, and appreciating that the crank 22 revolves clockwise, it will be understood that the roller 23 picks up the arm 25 near its outward end and moves the mechanism upward, the hammer 33 moving vertically in its bearing and the rollers 28 and 31 being held in the guideway 29. As the crank 22 rotates clock-

wise, it will be appreciated that its leverage action through the roller 23 in the slide 24 is relatively slow, but after the crank passes the horizontal it becomes faster and faster, reaching its maximum high speed leverage when the crank reaches the opposite horizontal position. Therefore, the hammer 33 is raised slowly and then driven downward faster and faster as the links 30 and 32 are held in straight line position by the guides 29, reaching its maximum driven speed at the right hand horizontal position of the crank 22. The hammer being relatively heavy, it will then move faster than the drive mechanism and this explains the necessity for the over-ride drive clutch 15.

The hammer 33 has an anvil shoulder 33' on its bottom end which strikes an anvil 34' which is lightly spring-retained upward by a compression spring 35'. The anvil 34' in turn strikes the tool bit 36 on which the hammer is supported by the collar 36' and which may be of any desired form and which is held in a conventional manner by a swinging holder 37.

Now it will be readily appreciated that the tool bit 36, being used for all manner of purposes, may be driven rapidly or slowly in accordance with the character of the work to which it is applied, and, therefore, the hammer 33 may be stopped in its travel over a considerable range. When a short stroke occurs the drive arm 25 may slide inward on the slide bracket 27 and the links 30 and 32 may pivotally collapse in order to permit the crank 22 to continue to rotate. It will, therefore, be apparent that I have developed a mechanism wherein the hammer 33 is picked up by levers, then driven downward with great force in a manner which permits free hammer action. It will also be apparent that the hammer action is completely developed within the hammer itself by inertia forces and the re-active forces will be absorbed within the hammer and not transferred to any extent to the operator.

Having thus described my invention, I claim:

1. In a power hammer, a frame structure, a hammer slidable in said frame, power means mounted on said frame, transmission means, including a manual and over-riding clutch, a rotatable crank driven by said transmission, a pivotal and slidable lever actuated by said crank, toggle links connecting said lever and hammer, means to hold said lever and links in driving relation to the hammer, and means to permit free pivotal action of said lever and links when the hammer ends its power stroke, whereby the rotatable crank and lever mechanism may continue to operate freely under variable strokes of the hammer.

2. In a power hammer, a frame structure, a hammer slidable in said frame, power means

5 mounted on said frame, a rotatable crank drivable by said power means, means to control the rotation of said crank, a pivotal and slidable lever actuated by said crank, toggle links connecting said lever and hammer, means to hold said lever and links in driving relation to the hammer, and means to permit free pivotal action of said lever and links when the hammer ends its power stroke, whereby the rotatable crank and lever mechanism may continue to operate freely under variable strokes of the hammer.

3. In a power hammer, a frame structure, a hammer slidable in said frame, power means mounted on said frame, a rotatable crank drivable by said power means, means to control the rotation of said crank, lever and link mechanism connecting said crank and hammer, for direct rotating and reciprocating motion, and guide means to control said connecting mechanism to provide direct reciprocating motion to the hammer on its lift and down drive strokes, but to loosen said connection and to permit independent rotation of the crank when the hammer is near the end of its drive stroke.

4. In a power hammer, a frame structure, a hammer slidable in said frame, a lever and link mechanism attached to said hammer, a rotatable crank to actuate said mechanism, power means to drive said crank and control means co-acting with said lever and link mechanism to provide direct reciprocating drive connection to the hammer until near the end of its driving stroke where the hammer is freed from said direct connection to permit independent rotation of the crank.

5. In a power hammer, a frame, a hammer slidably mounted in the frame, a lever and link mechanism attached to said hammer, a rotatable crank to actuate said mechanism and reciprocate the hammer, the arrangement of the crank and link mechanism providing a faster down stroke of the hammer than its up stroke, power means to drive the crank, and an over-riding clutch between said power means and crank to permit faster rotation of the crank than its normal driven speed.

6. In a power hammer, a frame, a hammer slidably mounted in the frame, a lever and link mechanism attached to said hammer, a rotatable crank to actuate said mechanism and reciprocate the hammer, the arrangement of the crank and link mechanism providing a faster down stroke of the hammer than its up stroke, power means to drive the crank, and control means coacting with said lever and link mechanism to provide direct reciprocating drive to the hammer until near the end of its driving stroke where the hammer is freed from said direct connection to permit independent rotation of the crank.
